UNITED STATES PATENT OFFICE

165,028

COMBINED VAPORIZER CASING AND MOUNTING BRACKET

Irving J. Sacks, Brooklyn, N. Y., assignor to
Remington Products Corporation, Elizabeth,
N. J., a corporation of New Jersey

Application December 12, 1950, Serial No. 13,403

Term of patent 7 years

(Cl. D31—3)

To all whom it may concern:

Be it known that I, Irving J. Sacks, a citizen of the United States, residing in the Borough of Brooklyn, Kings County, in the city and State of New York, have invented a new, original, and ornamental Design for a Combined Vaporizer Casing and Mounting Bracket, of which the following is a specification, reference being had to the accompanying drawings, forming a part hereof, of which:

Fig. 1 represents a side elevation of a combined vaporizer casing and mounting bracket, showing my new design;

Fig. 2 is a top plan view thereof;

Fig. 3 is a front elevational view thereof; and

Fig. 4 is a vertical section through the connecting bracket and a rear elevational view of the casing of the unit, taken at 4—4, Fig. 1.

The dominant features of my design reside in the portions shown in full lines.

What I claim is:

The ornamental design for a combined vaporizer casing and mounting bracket, substantially as shown and described.

I. J. SACKS.
